UNITED STATES PATENT OFFICE.

VINCENT J. CONCES, SR., OF EAST CHICAGO, INDIANA.

CASTINGS SHAKING AND JOLTING MACHINE.

1,216,212.

Specification of Letters Patent. Patented Feb. 13, 1917.

Application filed July 28, 1916. Serial No. 111,917.

To all whom it may concern:—

Be it known that I, VINCENT J. CONCES, Sr., a citizen of the United States, residing at East Chicago, in the county of Lake and 5 State of Indiana, have invented new and useful Improvements in Castings Shaking and Jolting Machines, of which the following is a specification.

This invention is an improved machine 10 for shaking and jolting flasks with the castings therein and thereby shaking the sand and castings out of the flasks and also shaking the sand out of the hollow castings, the object of the invention being to provide an 15 improved machine of this character which is strong and durable, is simple in construction, which may be operated by means of an electric or other suitable motor, and which enables the sand and castings to be 20 shaken out of the flasks without danger of injury to either the flasks or to the castings.

The invention consists in the features of construction, combination, and arrangement of devices, hereinafter fully described and 25 claimed.

In the accompanying drawings:—

Figure 1 is a vertical sectional view of a 30 castings shaking and jolting machine constructed and arranged in accordance with my invention.

Fig. 2 is a plan of the same.

Fig. 3 is a horizontal sectional view of the 35 same on the plane indicated by the line 3—3 of Fig. 1.

Fig. 4 is a detail transverse sectional view of the same.

Fig. 5 is a detailed plan of the shaking and jolting table.

The body 1 of the machine is preferably 40 a single casting, is hollow and comprises a top 2, walls 3, a base flange 4, cross bars 5, 6, in the base and braces 7 on the inner sides of the walls, and which connect cross bars to the top. The bottom of the body is here 45 shown as open. Pillow brackets 8, of which four are here shown, and which may be provided in any suitable number, are secured in the body, the two outermost pillow brackets being secured to opposite walls of the 50 bracket by bolts 9 and these pillow brackets are provided with bearings 10 for a shaft 11. The said shaft is provided at a point intermediate its ends with a shaking and jolting arm 12 in the outer arm of which an anti-friction roller 13 is mounted for rotation. The said shaft is provided with a spur gear 55

14. Said spur gear is engaged by a smaller gear 15 on a shaft 16 which is mounted in suitable bearings 17 and said gear 15 is also engaged by a smaller driving gear 18 60 which is on a shaft 19. Said shaft 19 is mounted in suitable bearings 20 and is connected to the driving shaft of a motor 21, which is preferably an electric motor and which in practice may be a motor of any 65 suitable type. It will be understood that when the motor is in operation, the shaft 11 with its shaking and jolting arm 12 will be revolved steadily and evenly at a desired rate of speed by the gears.

A hollow standard 21 which is preferably 70 tubular, rises from the center of the top of the body and is provided with radial braces 22. At its upper end, the said standard is also provided with radially arranged 75 guide arms 23.

A shaking and jarring table 24 is also provided which comprises flange sides 25, cross arms 26, brace arms 27 which are arranged in the corners of the table and in 80 the angles between the cross arms and bars 27 which are also arranged in the corners of the table and extend between the flange walls of the table, said radial arms and said cross arms. The corners of the table between the 85 cross arms are open and said brace arms 27 and bars 28 form in effect, grate elements in the corners of the table. The cross arms 26 are hollow and are open on their lower sides to receive the cross guide arms of the standard and permit vertical reciprocating movement of the table on the upper end of the 90 standard. At its center, the table is also provided with a vertical depending shaking and jolting bar 30 which is preferably cylindrical 95 in form and fits in and extends down through the standard and is vertically movable therein, the lower end of said shaking and jolting bar extending down into the upper portion of the body and being arranged in the path of the arm 12 of the 100 shaft 11, so that at each rotation of said shaft 11, the roller 13 will strike the lift and pass under and permit the bar 30 to drop, so that the table will be alternately lifted 105 and dropped violently and thus shaken and jolted in rapid succession.

Flasks with the castings therein will be placed on the shaking and jolting table and the operation of the machine serves to 110 thoroughly shake and jolt the sand and castings out of the flasks and to also shake and

jolt the adhering sand out of the hollow castings, the sand dropping down through the spaces between the grated portions of the table and the castings being caught and held on the table and prevented from being injured.

Chutes 31 are arranged on opposite sides of the standard and discharge the sand beyond opposite sides of the body and into pits 10 which are formed on opposite sides of a foundation base 32 on which the body is bolted. This foundation base is made of reinforced concrete and is embedded in the ground.

A plane table, such as shown at 34 in Fig. 5 may be substituted for the grated table within the scope of my invention, when it is desired to subject flasks to only a shaking and jarring process and without 20 screening sand therefrom.

From the foregoing description, taken in connection with the accompanying drawings, the advantages of construction and of the method of operating will be readily apparent to those skilled in the art to which the invention relates, and while I have described the principles of operation of the device together with the device which I now consider to be the best embodiment thereof, 30 I desire to have it understood that the device shown is merely illustrative and that such changes may be made when desired as are within the scope of the appended claims.

Having described the invention, what is 35 claimed is:

1. In a machine of the class described, a body having a hollow standard provided with radially arranged guide arms, a table having a depending shaking and jarring bar 40 arranged for vertical movement in the stand-

ard and also having radially arranged arms coacting with those of the standard to guide the table, the table being further provided with openings between said arms, and means to lift and drop the shaking bar and thereby 45 impart vertical shaking and jarring movement to said bar and said table.

2. In a machine of the class described, a body having a hollow standard and also having radially arranged braces and radially 50 arranged guide arms at the upper ends of said braces, a table having a depending shaking and jarring bar arranged for vertical movement in the standard and also having hollow guide arms coacting with those of 55 the standard to vertically guide the table, and openings between said hollow guide arms, chutes arranged on opposite sides of the standard and below the table and means to lift and drop the shaking bar and thereby 60 impart vertical shaking and jarring movement to said bar and said table.

3. In a machine of the class described, a body having a hollow standard and radially 65 arranged guide arms at the upper end of the standard, a table having depending side flanges engaging over the outer ends of said guide arms, the table being further provided with hollow guide arms engaging those of the standard and with openings between 70 said hollow guide arms and said side flanges, and being also provided with a depending shaking and jarring bar arranged for vertical movement in the standard, and means to lift and drop the shaking bar and thereby 75 impart vertical shaking and jarring movement to said bar and said table.

In testimony whereof I affix my signature.

VINCENT J. CONCEZ, Sr.
